ENGINE CONTROL APPARATUS

John B. Dyer, Pendleton, Ind., assignor, by mesne assignments, to General Motors Corporation, Detroit, Mich., a corporation of Delaware

Application November 19, 1932, Serial No. 643,378

29 Claims. (Cl. 290—37)

This invention relates to apparatus for controlling the operation of internal combustion engines, more particularly those of automotive vehicles and specifically to apparatus for controlling the starting devices of such engines.

It is one object of this invention to provide electrically operated means for rendering the starting apparatus operative to start the engine, which is caused to operate in response to the operation of one or more of the control devices which must be actuated by the operator of the engine or vehicle to control the operation thereof under ordinary operating conditions.

A further object of the invention is to provide electrically operated means of this character which is rendered inoperative by one or more of the several variable functions of the engine and is so controlled thereby that said electrically operated means is prevented from becoming operative as long as the engine is running under its own power.

According to this invention, these objects are accomplished by the provision of an electromagnet which is operative to simultaneously close the starting motor switch and shift the motor-operated driving pinion into mesh with the engine flywheel gear, said electromagnet being energized upon closing of the ignition switch and a switch operated by the accelerator pedal which controls the position of the carburetor throttle to regulate the quantity of combustible mixture which is supplied to the combustion chambers of the engine. This electromagnet is adapted to be de-energized either by the action of engine suction, or by a counter-voltage set up by the generator, or by both these means, so that the starting motor is rendered inoperative when the engine is operating under its own power and remains inoperative as long as the engine continues to run.

Further objects and advantages of the present invention will be apparent from the following description, reference being had to the accompanying drawings wherein a preferred embodiment of one form of the present invention is clearly shown.

In the drawings:

Fig. 1 is a wiring diagram of one form of the present invention in which the starting motor is rendered inoperative by action of engine suction.

Fig. 2 is a wiring diagram of a modified form of the invention in which the starting motor is rendered inoperative by action of the generator.

Fig. 3 is a wiring diagram showing a further modification in which the action of engine suc-

tion and the generator are both employed to prevent operation of the starting motor during operation of the engine.

Fig. 4 is a detail sectional view of an automatic relay switch controlled by engine suction and the generator.

Referring to Fig. 1 of the drawings, the starting motor is indicated at 20 and has an armature shaft 22 on which is splined a sleeve 24, which is secured to one member of an over-running clutch 26, the other member of which is secured to, or integral with, a driving pinion 28 adapted to be moved into engagement with the gear 30 formed on the engine flywheel in order to turn said gear and start the engine whenever the starting motor is operated. The sleeve 24 is moved to the right in Fig. 1 in order to effect engagement of the pinion 28 with the flywheel gear 30 and simultaneously the circuit between the starting motor 20 and the battery is closed by means which will now be described, in order to cause the starting motor to become operative.

To this end the sleeve 24 is provided with a grooved collar 32 which is slidable on the sleeve 24 and said collar is engaged by a pin 34 which projects from the lower end of a lever 36 suitably pivoted at 38 and pivotally connected at its upper end with the armature 40 of a solenoid, which is indicated in its entirety by the reference character 42. The lower part of the lever 36 may be bifurcated to form a yoke and there may be two pins secured to both arms of the yoke if so desired. When the solenoid 42 is energized, the lever 36 is moved in a counterclockwise direction and through the medium of the collar 32, compresses a spring 44 which surrounds the sleeve 24 between the collar 32 and the clutch 26 to move the pinion 28 into engagement with the flywheel gear in the usual manner and at the same time the left end of the armature 40 operates the movable contact member 46 of the main starting motor switch to close the starting motor circuit and cause the starting motor to become operative.

The starting motor is grounded through the connection 48, while a wire 50 leads from the starting motor to a fixed contact 52 and a second fixed contact 54 is connected by a wire 56 with a wire 58 which leads from the generator hereinafter described, to a battery 60 grounded through the connection 52. The movable contact 46 is normally held out of engagement with the contacts 52 and 54 by a spring 62, but upon energization of the solenoid 42, the contact 46 is moved so as to engage both of the fixed con-

tacts 52 and 54 and close the circuit of the starting motor. When this takes place, current will flow from the battery 60 to ground through the connection 62 and from the battery through wires 58 and 56, contacts 54, 46, 52 and wire 50 to the starting motor and thence through connection 48 to ground again.

The starting motor will cause the engine to start and when running under its own power, the starting motor is rendered inoperative by means afterwards described, at which time the lever 36 and the parts operated thereby will be moved to normal position with the pinion 28 out of engagement with the gear 30.

The operation of the solenoid 42 is both manually and automatically controlled, the solenoid being caused to become energized upon the operation of certain manually operated switches, but is de-energized by the action of engine suction. This suction is insufficient to cause de-energization of the solenoid during the time the engine is being turned by the starting motor, but becomes sufficient to effect this function when the engine starts to operate under its own power and the device is so constructed that the energization of the solenoid is prevented as long as the engine continues to so operate.

In order to control the operation of the solenoid in this manner, it is provided with a winding 66 which is grounded at 68 and is connected at its other end with a wire 70 which leads to one fixed contact 72 of an automatic suction operated switch hereinafter described in detail and indicated in its entirety by the reference character A. This suction operated switch includes a movable contact member 74 which is adapted to engage the fixed contact 72 and another fixed contact 76 when the switch is closed, the fixed contact 76 being connected by wire 78 with a binding post 80 electrically connected to a fixed contact 82 of a switch indicated in its entirety by the letter B and adapted to be operated by the accelerator pedal which controls the quantity of combustible mixture supplied to the engine. The fixed contact 82 is adapted to be engaged by a movable contact 84 electrically connected to a binding post 86 when the accelerator pedal 87 is operated to open the carburetor throttle. The binding post 86 is connected by a wire 88 with a wire 90 leading from the fixed contact 92 of the ignition switch to the ignition system of the engine. The ignition switch comprises also a movable contact 94 connected by wire 96 with the wire 58 which leads to the battery. It will be obvious, therefore, that when the engine is stopped and the ignition switch is closed, if the operator of the vehicle operates the accelerator pedal to bring the contacts 84 and 82 into engagement, that current will flow from the battery through the connection 62 to the ground and from the battery through the wires 58 and 96, the ignition switch, wire 88, the switch B, wire 78, the switch A which is normally closed when the engine is not running, and wire 70 to the winding 66 and thence through the connection 58 to ground again. The circuit through the winding 66 is thus closed which causes the solenoid to become energized to effect closing of the starting motor switch and the shifting of the motor driven pinion 28, as previously described. This circuit will remain closed until the action of engine suction causes such circuit to be broken by the opening of the switch A, because, as will be noted later, the switch B remains closed during the running of the engine under its own

power except during such time as the accelerator pedal may be permitted to return to normal position as when the engine is idling. In this form of the invention, the generator is indicated by the reference numeral 98, being grounded by the connection 100 and connected by a wire 102 with the wire 58, a cut-out relay of conventional form being provided at 104. This generator, in this form of the invention is preferably of the conventional type as illustrated in Fig. 1, for in this form of the invention the generator performs only its charging function and has no controlling effect on the action of the starting motor, the latter being entirely controlled by the manually operated ignition switch and switch B and the automatically operated switch A.

The switch B which is operated by the accelerator pedal, is of substantially the same construction as is described in applicant's co-pending application Serial No. 594,553 and comprises an outer housing or sleeve 108, which is secured in any desirable way to the upper end of a rod 110, which extends to the carburetor throttle, as more fully shown in Fig. 3, the construction of the switch B being the same in all of the modifications of the invention disclosed in this application. Received within the outer sleeve 108 is an inner sleeve 112 in which is received a piston 114 secured in any suitable way to the lower end 30 of a short rod 116, which extends through an opening in a reduced neck of the outer sleeve 108, which forms the bearing surface for the rod 116. The accelerator pedal 87 is secured to the end of this rod and a spring 120 which surrounds 35 the rod between the pedal or button 87 and the end of the outer sleeve 108, normally holds the parts in the relative position shown in the drawings, such spring being compressed whenever the button 87 is operated. The inner sleeve 112 supports 40 a block of insulating material 122 which projects through a slot 124 formed in the outer sleeve 108 and supports binding post 86 which is screwed into a metallic socket carried by the block 122. The binding post is electrically connected in any suitable way to the contact 84 which is also supported in the insulating material 122. The block of insulating material 126 is supported in the outer sleeve 112 and is fixed 45 relative thereto in any suitable way, a projecting portion of this block extending through the slot 124 as previously described. Binding post 80 is supported in this extension and is suitably connected with the fixed contact 82 also supported by the block 126. A spring 128 surrounds the rod 110 between some suitable fixed member and the housing 108, this spring being operative to restore the above described assembly to normal 50 position when the operator's foot is removed from the button or pedal 87. Another spring 130 is received between the piston 114 and the block 122.

The operation of the switch B is substantially as follows. When the button 87 is pressed by the operator, the piston 114 first moves downwardly compressing the spring 130 until the inner sleeve 112 is moved, carrying the movable contact 84 into engagement with the fixed contact 82 which completes the circuit through the winding of the solenoid. After this movement the entire assembly moves as a body when the pressure is sufficient to overcome the force of the spring 128 moving the throttle to whatever position is desired by the operator, the spring 120 and spring 130 combine, being of less strength than the spring 128. The energization of the solenoid

causes the engine to be started as previously described and when the engine begins to run under its own power, the switch A, which will now be described, is opened to break the circuit through the solenoid. The operator may release the button 81 to permit idling of the engine, or he may continue to hold the accelerator pedal in depressed position subsequent to the starting of the engine. In the latter event, the contacts 84 and 82 will remain in engagement, but since the circuit through the solenoid is broken by the switch A, the starting motor cannot be rendered operative notwithstanding the fact that the switch B is closed.

The switch A comprises a sheet metal shell 140 which is secured to another sheet metal shell 142 by any suitable fluid tight joint to form a diaphragm chamber and between flanges projecting from the two shells, a flexible diaphragm 144 is clamped. On one side of the diaphragm is a sheet metal disk 146 and on the other side of said diaphragm, two sheet metal disks 148 and 150 respectively while extending through the diaphragm and the three disks is a pin 152 provided with a shoulder which engages the disk 146 and being riveted at the opposite end to hold the entire assembly together, the disks operating to reinforce the diaphragm. The pin 152 is secured to, or is integral with the movable switch contact 74 hereinbefore referred to and said contact is moved into and out of engagement with the fixed contacts 72 and 76 to open and close the switch by action of the diaphragm. The fixed contacts are supported by the shell 142, being suitably insulated therefrom. A nipple 154 having flange 155 extends through an opening in the shell 140 and a washer 156 externally threaded on the nipple clamps the shell 140 between itself and the flange to form an air-tight joint. A coupling member 158 is threaded on the nipple 154 and serves to connect the nipple with a tube 160 of suitable flexible material, such as copper, which extends to and is suitably connected with the intake manifold. A spring 162 is received within the nipple and engages the disk 148 to hold the diaphragm normally in the position shown in the drawings with the movable contact 74 in engagement with the fixed contacts 72 and 76.

Obviously when the engine begins to run under its own power, the suction communicated from the manifold through the tube 160 moves the diaphragm 144 to a position to disengage the movable contact from the two fixed contacts of the switch A in order to break the circuit through the solenoid and the device is so constructed that the suction is sufficient under all normal operating conditions to hold the switch A open whenever the engine is running under its own power, so that notwithstanding the fact the ignition switch and the switch B may both be closed, it is impossible to close the circuit through the solenoid at any time while the engine is running under its own power.

In the form of the invention disclosed in Fig. 2, the construction is much the same as that previously disclosed, but for the fact that a magnetic switch controlled by the generator is substituted for the switch A. The construction of the starting motor, the solenoid and the mechanism operated thereby is exactly the same as that previously described and the description thereof need not be repeated, such parts of these devices as are shown in Fig. 2 being indicated by the same reference characters as are used in Fig. 1 with the suffix *a* added.

Substituted for the switch A is a magnetic switch indicated in its entirety by the reference character C. This switch is indicated in the diagram in substantially the same relation as is the switch A of the form of the invention shown in Fig. 1 and previously described. A wire 70a extends from one end of the winding of the solenoid to a fixed contact 170 which is adapted to be normally engaged by a movable contact 172 carried by the armature 174 of an armature magnet of any conventional design and normally held open by a compression spring 176. The movable contact 172, when in switch closing position, engages a second fixed contact 178 connected by a wire 78a with the binding post 80a of the switch B. The ignition switch in this form of the invention preferably comprises two fixed contacts 92a and 93a, to which are connected wires 90a and 91a leading to the ignition system and gasoline gauge respectively. The switch also comprises a movable contact member having two contact arms 94a and 95a to engage the two fixed contacts above referred to. In this device when the ignition switch B and switch C are both closed, current will flow from the battery 60a through the wire 62a to ground and through the wire 58a, wire 96a, the ignition switch, wire 91a, wire 88a, switch B, wire 78a, switch C, and wire 70a to the solenoid winding and through connections 68a to ground again, thus completing the circuit of the solenoid and causing the operation of the starting motor and the meshing of the driving pinion with the flywheel gear as previously described.

35. The switch C is normally open, but is closed when both the ignition switch and the switch B are closed because the closing of these switches energizes the winding of the solenoid of said magnetic switch C to effect movement of the contact 172. For this purpose the wire 102a, which leads from the generator, is connected by a wire 180 with one end of the winding 182 of the above mentioned solenoid, the other end of said winding being connected to the wire 78a which leads from the fixed contact 178 to one of the fixed contacts of the switch B.

When the ignition switch and the switch B are both closed, current passes from the battery to ground and from the battery through wires 58a and 96a, the ignition switch, wires 91a and 88a, the switch B, and wire 78a to the winding 182 and thence through the wire 180 to the generator 98a and through the connection 100a to ground, thus completing the circuit through the winding 182, energizing the magnetic switch C, and causing the contact 172 to move into engagement with contacts 170 and 178. When the engine is running under its own power, the generator is operated at sufficient speed to set up a counter-voltage in the winding 182 through the connection thereof with the wire 102 leading from the generator, which is sufficient to de-energize the magnet of the switch C enough to permit the spring 176 to open the switch.

65. In this modification of the invention it is also possible to use a generator of the ordinary type, but it is preferable to employ a separately excited generator, as such form of generator will effect the opening of the magnetic switch C when it is operating at a lower speed than the ordinary type of generator. This is a great advantage in this type of apparatus because under certain conditions the engine under very heavy load, operates at a very low speed with the generator 70 running at a correspondingly low speed and it is

desirable to maintain the magnetic switch open at as low an engine speed as possible in order to prevent any possibility of the circuit through the solenoid 42a being closed unless the engine actually comes to a stop. Otherwise, the starting motor might become effective while the engine is still operating, even though said engine is operating at a very low speed. This would result in damage to the mechanism such as breaking the teeth of the pinion or flywheel gear. Therefore, in the form of the invention shown in Fig. 2, the generator is illustrated as of the separately excited type, the third brush thereof being connected by the wire 105a to the wire 91a leading from one fixed contact of the ignition switch to the gasoline gauge.

Obviously, the operation of this modified form of the device is substantially the same as that of the first form but for the fact that the switch C is controlled by the generator instead of by engine suction as is the switch A.

In the form of the invention shown in Figs. 3 and 4, the construction is much the same as that of the previously described forms but for the fact that in this form the solenoid which controls the operation of the starting motor and shifting of the driving pinion is controlled by the joint action of the generator and engine suction, a secondary or relay switch indicated in its entirety by the reference letter D, being provided for this purpose and described in detail herein-after. Those parts of this form of the invention which are of the same construction as those disclosed in the preceding figures are not specifically described, but are indicated on the drawings by the same characters as in Fig. 1 with the suffix b added. The starting motor 20b and the mechanism operated thereby, as well as the solenoid 42b and devices associated therewith, are of substantially the same construction in this modification as shown in Fig. 1. Also the construction of the switch B is the same as in Fig. 1. In this form of the invention the winding of the solenoid 42b is grounded at 88b and connected by a wire 70b to a binding post 196 electrically connected to a fixed contact of the secondary switch D, while another binding post 192 is electrically connected to a movable contact of said switch D operated in a manner to be later described. The binding post 192 is connected by a wire 195 with the wire 58b which leads from the generator to the battery. When the fixed and movable contacts of the secondary switch D are closed, it will be obvious that current will flow from the battery to ground through the connection 62b and from the battery through wires 58b and 194 to the binding post 192, through switch D and the wire 70b to the winding of the solenoid 42b and thence through the connection 68b to ground. Hence, when the switch D is closed, the circuit from the battery through the solenoid 42b is completed and said solenoid is immediately effective to cause the operation of the starting motor and the shifting of the driving pinion 20b as previously described. The closing of the switch D is effected by the operation of the ignition switch and the switch B operated by the accelerator pedal. To this end the binding post 88b of the accelerator switch B is connected by a wire 86b with the wire 64b leading from the ignition switch to the ignition system of the engine in the same way as in Fig. 1, but the binding post 88b is connected by a wire 193 with one end of the winding of a magnet which forms a part of the switch D, the other end of said winding being connected by a

wire 198 with the generator 20b which is grounded at 100b, as shown in Fig. 3. As will be pointed out more specifically later, the switch D is normally open when the engine is stationary and upon closing of the ignition switch and the switch B, the winding of the magnet of said switch D is energized, closing the switch and completing the circuit through the pinion shifting solenoid 42b, as previously described. It will be clear from the foregoing that when the ignition switch is closed and the switch B is closed, current flows from the battery to ground through the connection 62b and through wires 58b, 95b, the ignition switch 88b, switch B, wire 196, the winding of switch D and wire 198 to the generator and through the connection 100b to the ground, thus effecting energization of the magnet of the secondary switch D. The switch D will now be described specifically. Switch D comprises fixed and movable contacts 200 and 202, electrically connected with the binding posts 196 and 192 respectively. These contacts are supported in a cup-shaped sheet metal member 204 which projects from and is secured in any desirable way to a cup-shaped housing 206 surrounding the winding 208 of the magnet previously referred to. The housing 206 is secured in any suitable manner to a cup-shaped metal shell 210 which is joined to a similarly shaped metal shell 212 in any suitable way to form a fluid-tight joint, while between flanges projecting from these shells is clamped the flexible diaphragm 214. This diaphragm is preferably non-metallic and is adapted to be operated by the suction of the engine. The winding of the magnet surrounds a core 218 while the armature 216 carries a rod 220 adapted to engage and operate the movable switch contact 202 as the diaphragm is moved back and forth, the rod 220 having a reduced portion, one end of which extends through the armature and the diaphragm as well as through three metal disks 222, 224 and 226, located on opposite sides of the diaphragm, the head of the rod being riveted on the disk 226 to hold the entire assembly together. Extending through an orifice in the shell 212 is an externally threaded and flanged nipple 228, the shell 212 being clamped between the flange and a washer 230 threaded on the nipple. A reduced coupling 232 is also screwed on the nipple and is provided with a reduced threaded portion 234 adapted to be connected in any desirable way with a tube 235 of copper or some other suitable flexible material and which extends to the intake manifold 237 so as to communicate the engine suction to the diaphragm chamber. A disk 236 with a minute orifice therein, is received between the end of the nipple 228 and the reducing coupling 232, while a spring 238 which normally holds the parts in the position shown in Fig. 4 when the engine is not in operation, is received between the disk 226 and the disk 236. The minute orifices are provided in the disk 236 for the purpose of delaying the return of the parts to normal position in the event that the engine suddenly stops immediately after starting, for a reason which will be more fully explained later. It will be noted that the movable contact 202 is carried by a flat spring which is engaged by the rod 220 and tends to move the rod to the right in Fig. 4, while the spring 238 tends to move the rod to the left, the effect of the two springs being to position the rod as shown with the contacts 200 and 202 separated.

Upon closing of the ignition switch and the

switch B with resulting re-energization of the magnet, the armature 218 is moved to the left to engage the switch contacts 208 and 202 and to cause energization of the solenoid 42b as previously described. The pull of the magnet is such that it would take a considerable degree of engine suction to effect separation of the above mentioned switch contacts by the suction pull on the diaphragm 214, but the operation of the generator when the engine begins to run under its own power sets up a countervoltage in the magnet reducing the pull thereof and permitting a very low suction to maintain the switch contacts 208 and 202 separated after they have once been disengaged and the engine is in operation. Also the disk 224 engages the shell 212 thus forming a magnetic seal, as more fully described in applicant's co-pending application Serial No. 589,642.

The delayed action produced by the disk 236, which is referred to above, is of importance because it prevents the immediate re-energization of the magnet and resulting closing of the secondary switch D which might otherwise take place immediately following any stopping of the engine substantially immediately after it was started. At such time the starting motor may be still in motion and if the solenoid 42 could be energized to cause the driving pinion to be moved into engagement with the flywheel gear, under such conditions damage might result. The specific construction of this secondary switch D forms no part of the present invention and is not covered by the claims therein.

In this form of the device also a generator of ordinary type may be employed, but for reasons set forth regarding the form shown in Fig. 2, it is desirable to employ a separately excited generator and for that reason such a form of generator is illustrated in Fig. 3. In Fig. 3 also there is shown diagrammatically the connection between the rod 113 and the carburetor throttle 240, which is positioned in the intake pipe 237, being secured to a shaft 242 journalled therein. On one end of the shaft 242 is a slotted arm 244 adapted to be engaged by a bent portion 246 of the rod 110 so that depression of the rod 110 will effect opening movement of the throttle. It will be apparent on consideration of Fig. 3 and Fig. 4 that the circuit through the solenoid 42b is completed upon actuation of the ignition switch and switch B so that the solenoid causes the starting of the engine, but when the engine begins to run under its own power, the circuit through the solenoid is broken by the combined action of the engine suction and the generator controlling the secondary switch D and this circuit will remain broken as long as the engine continues to run so that the starting motor cannot become operative during any operation of the engine under its own power.

While the form of embodiment of the present invention as herein disclosed, constitutes a preferred form, it is to be understood that other forms might be adopted, all coming within the scope of the claims which follow.

What is claimed is as follows:

1. Starting apparatus for internal combustion engines, comprising, a current source, a starting motor adapted to be operated by current from said source, an electromagnet for establishing driving connection between the starting motor and the engine for starting said engine, means for variably controlling the quantity of combustible mixture supplied to the engine while the

starting motor is being operated to start said engine, and means operated by said mixture controlling means for controlling the operation of said electromagnet.

2. Starting apparatus for internal combustion engines, comprising, a current source, a starting motor adapted to be operated by current from said source, an electromagnet for establishing driving connection between the starting motor and the engine for starting said engine, means for variably controlling the quantity of combustible mixture supplied to the engine while the starting motor is being operated to start said engine, means operated by said mixture controlling means for controlling the operation of said electromagnet, and means operated by the engine when it is operating under its own power for preventing energization of said electromagnet.

3. Starting apparatus for internal combustion engines, comprising, a current source, a starting motor adapted to be operated by current from said source, an electromagnet for establishing driving connection between the starting motor and the engine for starting said engine, means for variably controlling the quantity of combustible mixture supplied to the engine while the starting motor is being operated to start said engine, means operated by the mixture controlling means for causing operation of said electromagnet, a generator, and means operated thereby for preventing operation of said electromagnet during operation of the engine under its own power.

4. Starting apparatus for internal combustion engines, comprising, a current source, a starting motor adapted to be operated by current from said source, an electromagnet for establishing driving connection between the starting motor and the engine for starting said engine, means for variably controlling the quantity of combustible mixture supplied to the engine while the starting motor is being operated to start said engine, means operated by the mixture controlling means for causing operation of said electromagnet, and means operated by the suction of the engine for preventing operation of the electromagnet when the engine is operating under its own power.

5. Starting apparatus for internal combustion engines, comprising, a current source, a starting motor adapted to be operated by current from said source, an electromagnet for establishing driving connection between the starting motor and the engine for starting said engine, means for variably controlling the quantity of combustible mixture supplied to the engine while the starting motor is being operated to start said engine, means operated by the mixture controlling means for causing operation of said electromagnet, a generator, and means operated by the generator and engine suction for preventing operation of said electromagnet when the engine is running under its own power.

6. Starting apparatus for internal combustion engines comprising, a current source, a starting motor, a circuit between the starting motor and current source to enable said starting motor to be operated by current from said source, an electromagnet for establishing driving connection between the starting motor and the engine and for completing the circuit between the starting motor and current source to enable said starting motor to start the engine, means for variably controlling the quantity of combustible mixture supplied to the engine while the starting motor is

being operated to start said engine, means operated by said mixture controlling means for causing operation of said electromagnet, and means operated by the engine when operating under its own power to prevent operation of said electromagnet.

7. Starting apparatus for internal combustion engines comprising, a current source, a starting motor, a circuit between the starting motor and current source to enable said starting motor to be operated by current from said source, an electromagnet for establishing driving connection between the starting motor and the engine and for completing the circuit between the starting motor and current source to enable said starting motor to start the engine, means for variably controlling the quantity of combustible mixture supplied to the engine while the starting motor is being operated to start said engine, means operated by said mixture controlling means for causing operation of said electromagnet, a generator, and means operated by the generator when the generator is running under its own power to prevent operation of said electromagnet.

8. Starting apparatus for internal combustion engines comprising, a current source, a starting motor, a circuit between the starting motor and current source to enable said starting motor to be operated by current from said source, an electromagnet for establishing driving connection between the starting motor and the engine and for completing the circuit between the starting motor and current source to enable said starting motor to start the engine, means for variably controlling the quantity of combustible mixture supplied to the engine while the starting motor is being operated to start said engine, a switch for causing operation of the electromagnet when closed and adapted to be closed by operation of said mixture controlling means, a second switch in circuit with the winding of said electromagnet and operable by said mixture controlling means so as to be closed when the mixture controlling means is operated, and means operable by the engine when it runs under its own power for opening said second switch to cause said electromagnet to be de-energized.

9. Starting apparatus for internal combustion engines comprising, a current source, a starting motor, a circuit between the starting motor and current source to enable said starting motor to be operated by current from said source, an electromagnet for establishing driving connection between the starting motor and the engine and for completing the circuit between the starting motor and current source to enable said starting motor to start the engine, means for variably controlling the quantity of combustible mixture supplied to the engine while the starting motor is being operated to start said engine, a switch for causing operation of the electromagnet when closed and adapted to be closed by operation of said mixture controlling means, a second switch in circuit with the winding of said electromagnet and operable by said mixture controlling means so as to be closed when the mixture controlling means is operated, a generator, and means whereby the generator causes said second switch to be opened when the engine is operating under its own power in order to effect de-energization of the electromagnet.

10. Starting apparatus for internal combustion engines comprising, a current source, a starting motor, a circuit between the starting motor and current source to enable said starting motor to

be operated by current from said source, an electromagnet for establishing driving connection between the starting motor and the engine and for completing the circuit between the starting motor and current source to enable said starting motor to start the engine, means for variably controlling the quantity of combustible mixture supplied to the engine while the starting motor is being operated to start said engine, a switch for causing operation of the electromagnet when closed and adapted to be closed by operation of said mixture controlling means, a second switch in circuit with the winding of said electromagnet and operable by said mixture controlling means so as to be closed when the mixture controlling means is operated, and means operable by engine suction when the engine runs under its own power to cause the opening of said second switch in order to de-energize the electromagnet.

11. Starting apparatus for internal combustion engines comprising, a current source, a starting motor, a circuit between the starting motor and current source to enable said starting motor to be operated by current from said source, an electromagnet for establishing driving connection between the starting motor and the engine and for completing the circuit between the starting motor and current source to enable said starting motor to start the engine, means for variably controlling the quantity of combustible mixture supplied to the engine while the starting motor is being operated to start said engine, a switch for causing operation of the electromagnet when closed and adapted to be closed by operation of said mixture controlling means, a second switch in circuit with the winding of said electromagnet and operable by said mixture controlling means so as to be closed when the mixture controlling means is operated, a generator, and means operable by the generator and engine suction when the engine runs under its own power to cause the opening of said second switch in order to de-energize the magnet.

12. Starting apparatus for internal combustion engines comprising, a current source, a starting motor, a circuit between the starting motor and current source to enable said starting motor to be operated by current from said source, an electromagnet for establishing driving connection between the starting motor and the engine and for completing the circuit between the starting motor and current source to enable said starting motor to start the engine, means for variably controlling the quantity of combustible mixture supplied to the engine while the starting motor is being operated to start said engine, a switch for causing operation of the electromagnet when closed and adapted to be closed by operation of said mixture controlling means, a second switch in circuit with the winding of said electromagnet and effective when closed to cause said electromagnet to be energized, a second electromagnet for operating said second switch and operative to hold said second switch closed when energized, means for causing said second electromagnet to be energized when said first mentioned switch is closed, a generator, and means whereby the generator when the engine is operating under its own power, causes the second electromagnet to be de-energized and the second switch to be opened.

13. Starting apparatus for internal combustion engines comprising, a current source, a starting motor, a circuit between the starting motor and current source to enable said starting motor to

be operated by current from said source, an electromagnet for establishing driving connection between the starting motor and the engine and for completing the circuit between the starting motor and current source to enable said starting motor to start the engine, means for variably controlling the quantity of combustible mixture supplied to the engine while the starting motor is being operated to start said engine, a switch for causing operation of the electromagnet when closed and adapted to be closed by operation of said mixture controlling means, a second switch in circuit with the winding of said electromagnet and effective when closed to cause said electromagnet to be energized, a second electromagnet for operating said second switch and operative to hold said second switch closed when energized, means for causing said second electromagnet to be energized when said first mentioned switch is closed, a generator, means whereby the generator, when the engine is operating under its own power, causes the magnet to be de-energized and means operable by engine suction upon the second switch when the magnet is de-energized.

14. Starting apparatus for internal combustion engines comprising, a current source, a starting motor, a circuit between the starting motor and current source to enable said starting motor to be operated by current from said source, an electromagnet for establishing driving connection between the starting motor and the engine and for completing the circuit between the starting motor and current source to enable said starting motor to start the engine, means for variably controlling the quantity of combustible mixture supplied to the engine while the starting motor is being operated to start said engine, a switch for causing operation of the electromagnet when closed and adapted to be closed by operation of said mixture controlling means, a second switch in circuit with the winding of said electromagnet and effective when closed to cause said electromagnet to be energized, a second electromagnet for operating said second switch and operative to hold said second switch closed when energized, means for causing said second electromagnet to be energized when said first mentioned switch is closed, a generator in circuit with the winding of said second electromagnet and operative to build up sufficient counter voltage in said winding when the engine is operating under its own power to de-energize the magnet and enable said second switch to be opened.

15. Starting apparatus for internal combustion engines comprising a current source, a starting motor operable by current from said source, a circuit between the current source and starting motor, an electromagnet operable to establish driving connection between the starting motor and the engine and to complete said circuit when the magnet is energized, means for variably controlling the quantity of mixture supplied to the engine during starting and during operation of the engine under its own power, a control switch for the magnet operable when closed to cause said magnet to be energized, a second control switch operable when closed to cause the closing of the first control switch and held closed by the mixture control means as the latter is moved to different positions during starting and operation of the engine, and means operable by engine suction to open the first control switch when the engine is self-operative so as to cause the magnet to be de-energized even if the second control switch is closed.

16. Starting apparatus for internal combustion engines comprising a current source, a starting motor operable by current from said source, a circuit between the current source and starting motor, an electromagnet operable to establish driving connection between the starting motor and the engine to complete said circuit when the magnet is energized, means for variably controlling the quantity of mixture supplied to the engine during starting and during operation of the engine under its own power, a control switch for the magnet operable when closed to cause said magnet to be energized, a second control switch operable when closed to cause the closing of the first control switch and held closed by the mixture control means as the latter is moved to different positions during starting and operation of the engine, a generator, and means whereby the generator causes the first control switch to be opened when the engine is operating under its own power even if the second control switch is held closed by the mixture controlling means.

17. Starting apparatus for internal combustion engines comprising a current source, a starting motor operable by current from said source, a circuit between the current source and starting motor, an electromagnet operable to establish driving connection between the starting motor and the engine and to complete said circuit when the magnet is energized, means for variably controlling the quantity of mixture supplied to the engine during starting and during operation of the engine under its own power, a control switch for the magnet operable when closed to cause said magnet to be energized, a second control switch operable when closed to cause the closing of the first control switch and held closed by the mixture control means as the latter is moved to different positions during starting and operation of the engine, a generator, and means whereby the joint action of the generator and engine suction causes the first control switch to be opened when the engine is operating under its own power even if the second control switch is held closed by the mixture controlling means.

18. Starting apparatus for internal combustion engines comprising a current source, a starting motor operable by current from said source, a circuit between the current source and starting motor, an electromagnet operable to establish driving connection between the starting motor and the engine and to complete said circuit when the magnet is energized, means for variably controlling the quantity of mixture supplied to the engine during starting and during operation of the engine under its own power, a control switch for the magnet operable when closed to cause said magnet to be energized, a second electromagnet for operating said control switch and operable to hold said switch closed when the magnet is energized, a second control switch in circuit with the winding of the second magnet operable when closed to cause said magnet to be energized and held closed by the mixture control means as the latter is moved to different positions during starting and operation of the engine, a generator also in circuit with the winding of the second magnet and operable to de-energize said second magnet when the engine is self-operative to enable the opening of said first control switch irrespective of the second control switch.

19. Starting apparatus for internal combustion engines, comprising, a current source, a starting motor operable by current from said

source, means for establishing driving connection between the starting motor and the engine to enable the starting motor to start said engine, power operated means other than the starting motor for operating said last named means, means for variably controlling the quantity of combustible mixture supplied to the engine while the starting motor is being operated to start said engine, and means operated by the mixture controlling means for controlling the operation of said power operated means.

20. Starting apparatus for internal combustion engines, comprising, a current source, a starting motor operable by current from said source, means for establishing driving connection between the starting motor and the engine to enable the starting motor to start said engine, power operated means other than the starting motor for operating said last named means, means for variably controlling the quantity of combustible mixture supplied to the engine while the starting motor is being operated to start said engine, means operable by the mixture controlling means for controlling the operation of said power operated means and means operated by the engine for preventing the operation of the power operated means while the engine is running under its own power.

21. Starting apparatus for internal combustion engines, comprising, a current source, a starting motor operable by current from said source, means for establishing driving connection between the starting motor and the engine to enable the starting motor to start said engine, power operated means other than the starting motor for operating said last named means, means for variably controlling the quantity of combustible mixture supplied to the engine while the starting motor is being operated to start said engine, means operated by said mixture controlling means for causing operation of said power operated means, and means operated by engine suction for preventing the operation of the power operated means during operation of the engine under its own power.

22. Starting apparatus for internal combustion engines, comprising, a current source, a starting motor operable by current from said source, means for establishing driving connection between the starting motor and the engine to enable the starting motor to start said engine, power operated means other than the starting motor for operating said last named means, means for variably controlling the quantity of combustible mixture supplied to the engine while the starting motor is being operated to start said engine, means operated by said mixture controlling means for causing operation of said power operated means, a generator, and means operated by the generator for preventing operation of the power operated means during operation of the engine under its own power.

23. Starting apparatus for internal combustion engines, comprising, a current source, a starting motor operable by current from said source, means for establishing driving connection between the starting motor and the engine to enable the starting motor to start said engine, power operated means other than the starting motor for operating said last named means, means for variably controlling the quantity of combustible mixture supplied to the engine while the starting motor is being operated to start said engine, means operated by said mixture controlling means for causing operation of said power operated

means, a generator, and means operated by the generator and engine suction jointly for preventing operation of the power operated means during operation of the engine under its own power.

24. Starting apparatus for internal combustion engines comprising, a current source, a starting motor operable by current from said source, means for causing the starting motor to operate and start said engine, power operated means other than the starting motor for operating said last named means, mixture controlling means for variably controlling the quantity of mixture supplied to the engine while the starting motor is being operated to start said engine, means operated by the mixture controlling means for controlling operation of the power operated means, a member movable in accordance with some variable function of the engine and movable to different positions when the engine is self-operative and inoperative, and means operated by said member to prevent operation of the starting motor when the engine is self-operative.

25. Starting apparatus for internal combustion engines comprising, a current source, a starting motor operable by current from said current source and in circuit therewith, a power operated means also in circuit with the current source for rendering the starting motor effective to operate the engine, means for variably controlling the quantity of combustible mixture supplied to the engine when the starting motor is being operated to start the engine, a switch in the circuit between the power operated means and current source and closed by said mixture controlling means as the latter is operated to regulate the mixture supply, and another switch between the power operated means and current source, said last named switch being operated by engine suction to prevent operation of the starting motor when the engine is running.

26. Starting apparatus for internal combustion engines comprising, a current source, a starting motor operable by current from said current source and in circuit therewith, a switch for closing said circuit, power operated means for establishing driving connection between the starting motor and engine and concurrently closing said switch, means for variably controlling the quantity of combustible mixture supplied to the engine while the starting motor is being operated to start the engine, means operated by the mixture controlling means for causing operation of said power operated means, and operated by the engine when it becomes self-operative to cause the power operated means to become inoperative and effective, as long as the engine continues to run under its own power, to prevent operation of said power operated means.

27. Starting apparatus for internal combustion engines comprising a current source, a starting motor operable by current from said source, a power operated device for rendering the starting motor effective to operate the engine, means for variably controlling the quantity of combustible mixture supplied to the engine while the starting motor is being operated to start said engine, a plurality of means, including means operable by said mixture controlling means which must be operated to cause operation of said power operated device, a generator, and a single means controlled by the joint action of the generator and engine suction for preventing operation of said power operated device while the engine is running under its own power.

28. Control apparatus for internal combustion

engines comprising, a current source, a starting motor adapted to be operated by current from said source, means for variably controlling the quantity of fuel mixture supplied to the engine, a power operated means in circuit with said current source for rendering the starting motor effective to operate the engine, a switch in the circuit between the power operated means and said current source adapted to be closed by said mixture controlling means to render the starting motor effective, a generator and another switch between the power operated means and said current source adapted to be operated by the generator to prevent operation of the starting motor when the engine is running.

29. Control apparatus for internal combustion engines comprising, a current source, a starting motor adapted to be operated by current from said source, a switch for completing the circuit between the starting motor and the current source, power operated means for closing said switch to render the starting motor operative, a foot operated accelerator pedal for variably controlling the quantity of mixture supplied to the engine and a switch operated by said pedal to control the operation of said power operated means.

JOHN B. DYER.
